UNITED STATES PATENT OFFICE.

GEORGE STACKHOUSE, OF BERKELEY, CALIFORNIA, ASSIGNOR TO PACIFIC SPRING BED CO., OF BERKELEY, CALIFORNIA, A CORPORATION OF CALIFORNIA.

ARM-FORM FOR FURNITURE.

1,384,165.

Specification of Letters Patent. Patented July 12, 1921.

Application filed July 19, 1920. Serial No. 397,447.

To all whom it may concern:

Be it known that I, GEORGE STACKHOUSE, a citizen of the United States, residing at Berkeley, in the county of Alameda and 5 State of California, have invented certain new and useful Improvements in Arm-Forms for Furniture, of which the following is a specification.

This invention relates to forms for the 10 arms of upholstered chairs, davenport and the like.

The object of this invention is to provide a form which is installed with less labor and skill.

15 Another object of this invention is to provide a form which will keep its original shape after a weight has been placed upon it.

Referring to the drawing which forms a part of this specification:

20 Figure 1 is a side view of a chair form with my arm form in position thereon.

Fig. 2 is a side view of my improved arm form.

Fig. 3 is an end view of the same.

25 Referring more particularly to the drawing in which the same reference characters apply to the same part throughout, the

numeral 1 indicates a spirally formed arm form. The form 1 is adapted to encircle an arm member 2, which is an integral part of 30 the furniture and is securely fastened thereto.

Springs 3 are interposed between the upper edge of the form 1 and plates 4 which are secured to the member 2. The springs 3 35 assist in resisting a weight placed on the top of the arm.

Since the form is well secured to the arm member 2, any side force tending to displace the form is easily overcome.

Having described my invention, I claim:

1. The combination with a rigid arm member, of a spirally formed form surrounding said member, and a plurality of springs spaced between the arm member and 45 the form.

2. The combination with a rigid arm member, of a spirally formed form surrounding said arm member, a plate secured to said arm member, a plurality of springs 50 secured to said plate and said form, and spaced between the plate and the form.

In testimony whereof I affix my signature.

GEORGE STACKHOUSE.
